The ornamental design for a motion sensing lighted mat, as shown and described.

DESCRIPTION

FIG. 1 is a front left perspective of a new motion sensing lighted mat showing my new design; and,

FIG. 2 is an exploded view thereof.

The views of the motion sensing lighted mat not shown form no part of the claimed design. The dashed electrical lines and couplings, and the dashed “WELCOME” indicia and flower designs, refer to environmental elements only and form no part of the claimed design. The lights have emanating shade lines to indicate illumination.
